BOX AND FASTENER

David M. Holbrook, Portland, Oreg.

Application November 25, 1933, Serial No. 699,735

5 Claims. (Cl. 229—6)

My invention relates to ventilated packing cases.

The invention is primarily used as a packing case for live objects, as baby chicks and other live hatchery products, as turkeys and other fowl.

My invention is comprised primarily of a box-like structure having a removable top associated therewith, ventilating holes being disposed through the side walls and top of the box to facilitate a thermal flow of air therethrough.

I provide a plurality of channel-like projections at the top of the box, and these projections together with the top of the box are secured to the body of the box with a suitable clamping strap thereby fixedly to secure the top with the projections to the body of the box.

In the distribution of baby poultry from commercial hatcheries, the baby poultry are often within the shipping container for considerable periods of time and it is essential and necessary that the shipping containers be properly ventilated to reduce loss of poultry due to suffocation or to improper air. In making relatively large shipments as is done by commercial hatcheries often the shipping cases are piled one upon another thereby preventing a proper circulation of air therethrough.

Where the body and the top of the shipping container are secured together with string, cord or other like fastenings, often those handling the containers lift them by the cords or strings, sometimes breaking the fastening and permitting the baby poultry to become released from the containers.

My invention, however, provides a secure means for affixing the top to the container, and furthermore, as a plurality of mutually independent fasteners is provided, the likelihood of general failure is reduced, resulting in reduction of loss to the shipper or the carrier.

My invention also provides means whereby the depending sides of the top are reinforced at about their mid-length by being clamped against the body sides, thereby reducing the hazard of breakage due to improper handling.

Through the use of my new and improved device the shipping container is spaced apart from the walls of the carrier and from other walls permitting a free flow of air about the sides and ends of the shipping container, and the spacing of the containers one from another when piled permits a free flow of air through the top thereof.

The primary object of my invention consists in providing a container for the shipment of live objects, that will permit a free circulation of air through the container at all times.

A further object of my invention consists in so constructing and assembling a shipping container that it will remain spaced apart from other objects, both at the sides and ends, and the top.

A still further object of my invention consists in providing means for securing the top to the body of the container, that it may not be easily disengaged therefrom or removed without a definite effort being made to do so.

A still further object of my invention consists in so constructing the shipping container that it may be made at a minimum cost.

A still further object of my invention consists in so constructing the fastenings that they act as means for reinforcing the depending sides of the top members of the shipping containers.

A still further object of my invention consists in so constructing the fastenings and the projections that they may be used in conjunction with shipping containers now in general use.

With these and incidental objects in view, the invention consists in certain novel features of construction and combination of parts, the essential elements of which are set forth in the appended claims, and a preferred form of embodiment of which is hereinafter shown with reference to the drawing which accompanies and forms a part of this specification.

In the drawing:

Fig. 1 is a side view of a plurality of my new and improved shipping container, shown one piled above another and illustrating the same spaced apart from the wall of the room in which they are placed.

Fig. 2 is a perspective side end view of one of my new and improved shipping containers, shown as being fully assembled.

Fig. 3 is a fragmentary sectional side view of one of my new fastenings shown in place upon the container and being fixedly positioned thereupon and also showing the depending side of the top member of the container being embraced and reinforced by the fastening.

Fig. 4 is a sectional end view of the channel-like fastening disposed upon the top of the container. This view is taken on line 4—4 of Fig. 3, looking in the direction indicated.

Fig. 5 is a perspective end view of one of the channel-like members shown removed from the shipping container.

Fig. 6 is a fragmentary side view of a portion of the upper wall of the body of the container illustrating the fastening strap secured thereto and illustrating the free end of the strap upwardly extending from the end of the container to facilitate engagement with the channel-like member fixed upon the top of the container.

Fig. 7 is a top plan view of the body of the container illustrating the fastening strap in position for the placing of the lid thereupon.

Like reference characters refer to like parts throughout the several views.

1 is the body of the shipping container. Spaced breather holes 2 are provided in the side and end

wall thereof for the circulation of air, it being understood that the containers are to be used in handling oxygen consuming animal life such as baby chickens. 3 is the top of the container.

5 This is likewise provided with breather holes 4.

In shipping these containers, it is desirable that they be spaced from each other and from other articles in order that air may freely circulate to the aforesaid breather holes, and to this end I

10 have provided a sheet metal projecting spacer 5.

This consists of an inverted U-shaped member having a central portion 6 from which project the downwardly directed side walls 7 and 8, the latter diverging somewhat from each other, altogether

15 forming a channel-like structure having outwardly sloping side walls. The side walls are each provided with projecting legs 9 which are passed through slits 11 in the portions 10 of the top 3. The legs after having been passed through

20 the slits 11 are bent at right angles to secure the spacers to the top 3.

The spacers are so positioned with regard to the edges of top 3 that they project, the end 12 extending a predetermined distance beyond the

25 plane of the side wall 13 of the container body. This projecting portion is to provide for an air space 14 between the wall of the container and, for instance the wall of a car in which these articles are being shipped, or for that matter any

29 adjacent surface. Furthermore the height of the side walls 7 and 8 is sufficient to provide for a free circulation of air when the containers are stacked one on another, it being understood that the spacers are to provide for both lateral and

35 vertical spacing. In actual practice I have found that in the average size container but four spacers are required. These are to be located one over each side or end as shown in Figure 2.

In addition to the foregoing and cooperating with the spacers to the end of providing added means for securing the spacers to the containers,

340 I provide a metal fastening strap 17 for securing the top to the body of the container and to reinforce the fastening means of the spacers as aforesaid. This strap is passed through a slit 16

45 and has one of its ends bent over top 19 of container side wall 13. The end 18 is formed into a bend to clamp the strap to the container side wall. The other end 20 of strap 17 is passed

50 through a receiving slit 22 in the bow portion 6 of the spacer 5 and then bent around the end 23 thereof as shown in Figure 3. Strap 17 in being placed through slit 22, is positioned outside the

55 side 21 of top 3, thereby clamping the side 21 securely against the side 13 of the container body, and acting to reinforce the side 21 in its mid

60 region. This form of construction adequately secures the top 3 to the container 1. In addition to providing the spacing means hereto enumerated, spacers 5 by reason of their projecting portions provide means for handling the containers.

While the form of invention herein shown and described is admirably adapted to fulfill the objects primarily stated, it is to be understood that it is not intended to confine the invention to the embodiment herein shown and described, as it

65 is susceptible of embodiment in various forms, all coming within the scope of the claims which follow.

70 What I claim is:—

1. A new article of manufacture comprising a

shipping carton composed of a perforated body element and a perforated lid, fastening slits disposed in the oppositely disposed walls of the body element, a fastening strap passing through each of the slits and bent over upon itself about the wall of the body element, slits disposed within the top wall of the lid, channel shaped metal spacers secured to the lid, said spacers including legs extended through the last mentioned slits and bent to prevent withdrawal, the outer ends of which spacers outwardly extend from the side walls of the lid, a receiving slit disposed in the top wall of said metal spacer and so positioned as to receive the fastening strap therein.

2. In a device of the class described, the combination of a shipping carton composed of a body element and a lid, the side walls of the body element and the top of the lid being perforated with

80 spaced breather holes, metal fastening straps secured to the oppositely disposed walls of the body element and upwardly extending therefrom,

85 channel shaped metal spacers, means for securing the metal spacers to the lid, said spacers when

330 secured thereto having their outer ends outwardly projecting from the lid, and means for securing the metal straps to the metal spacers.

3. In a device of the class described, the combination of a shipping carton composed of a body element and a lid, the side walls of the body element and the top of the lid being perforated with

105 spaced breather holes, metal fastening straps secured to each of the walls of the body element and projecting upwardly therefrom, channel shaped metal spacers including extensions there-

110 of adapted for securing such metal spacers to the lid, said spacers when secured thereto projecting beyond the edge of the lid, and the projecting

115 portions of the metal straps extending through and being bent about the projecting ends of the metal spacers.

4. A new article of manufacture embodying a box and its lid, both provided with ventilation

120 holes, spacers for spacing such box at the top and sides to avoid coverage of such ventilation holes, said spacers having a substantially in-

125 verted U-shape transverse form the sides of which have extensions extending through the lid and being bent to prevent withdrawal, said

130 spacers each having an end portion projecting beyond the edges of the lid, and metallic straps each having one end secured to a side of the box

135 and its other end extended through and bent over the projecting end of a spacer.

5. A new article of manufacture embodying a box and its lid both provided with ventilation

140 holes, spacers for spacing such box at the top and sides to avoid coverage of such ventilation holes, said spacers each having a central portion with

145 downwardly directed sides divergently arranged with regard to each other which sides at their lower edges being provided with extension legs,

150 the spacers being positioned upon the top of the box with a portion projecting beyond the edge thereof and the legs extended through the top and bent to prevent withdrawal, and a fastening

155 strap for each spacer which fastening strap has one end extended through the side of the box and bent over its upper edge and its other end ex-

160 tended through the central portion of the spacer and bent over the end of the projecting portion.

DAVID M. HOLBROOK.
